UNITED STATES PATENT OFFICE.

ABRAM BERNSTEIN, OF NEW YORK, N. Y.

DESIGN FOR AN INSIGNIA, BADGE, OR EMBLEM.

56,337.

Specification for Design.

Patented Oct. 5, 1920.

Application filed April 23, 1918. Serial No. 230,346. Term of patent 3½ years.

To all whom it may concern:

Be it known that I, ABRAM BERNSTEIN, a citizen of the United States, residing at New York, borough of Bronx, New York, have invented a new, original, and ornamental Design for Insignia, Badges, or Emblems, of which the following is a specification, reference being had to the accompanying drawing, forming part thereof.

In the drawing Figure 1 is a plan view

of the insignia, badge or emblem, embodying the design.

Fig. 2 a side elevation.

I claim—

The ornamental design for an insignia, badge or emblem, as shown.

Signed at New York, N. Y., this 18th day of April, 1918.

ABRAM BERNSTEIN.
